UNITED STATES PATENT OFFICE.

ADNAH McMURTRIE, OF NEW YORK, N. Y., ASSIGNOR TO THOMAS & BETTS COMPANY, OF NEW YORK, N. Y., A CORPORATION OF NEW YORK.

PLASTER-HOLDER FOR OUTLET-BOXES.

No. 843,962.

Specification of Letters Patent.

Patented Feb. 12, 1907.

Application filed June 14, 1906. Serial No. 321,616.

To all whom it may concern:

Be it known that I, ADNAH McMURTRIE, of New York, N. Y., have invented certain Improvements in Plaster-Holders for Outlet-
5 Boxes, of which the following description, in connection with the accompanying drawings, is a specification, like letters on the drawings designating like parts.

This invention relates to outlet-boxes or
10 similar members for electrical conduit systems, and has for its object the provision of plaster-holders for such members.

It is especially applicable to boxes made of
15 pressed steel, which are usually smooth, and
therefor non-retentive of plaster when cov-
ered up by plaster in walls of ceilings and in
similar situations; but it will be understood
that my invention is not limited to use upon
20 boxes of pressed steel.

The various features of my invention will
be illustrated and described fully in the ac-
companying drawings and specification and
pointed out in the claims.

In the drawings, Figure 1 shows in perspec-
25 tive a box to which my invention has been
applied. Fig. 2 is a view, on an enlarged
scale, in longitudinal section of a plaster-re-
taining device constructed in accordance
30 with my invention. Figs. 3, 4, and 5 are
similar views of modified forms of such de-
vices, Fig. 6 showing in longitudinal section
still another modification applied to a box.

In the embodiment of my invention se-
lected for illustration and description as a
35 convenient form to enable ready and com-
plete understanding of my improvements the
reference-numeral 1 designates an outlet-box
of the type commonly used for interior con-
duit systems for electric wiring, which, with
40 its cover 2 and retaining-screws 3 for the
cover, may be and is shown as of well-known
pressed-steel construction, the material being
considered in this instance as pressed steel
merely for illustration.

45 In accordance with my invention I pro-
vide a plaster holder or retaining device 4,
secured to the box by the screw 3 and pro-
jecting above the cover 2 to such a height as
to engage the plaster covering the box after
50 it has been set in the wall, ceiling, &c., and
preventing the plaster from cracking away
from the cover of the box.

The device 4 is shown on an enlarged scale

in Fig. 2, where the reference-numeral 4 des-
ignates the plaster-retaining portion. 5 is a 55
body or attaching portion, the means for at-
tachment in this instance consisting of a cen-
tral aperture 6, through which the fastening-
screw 3 may be passed. This is a simple and
inexpensive form of the device and may be 60
applied to any existing box.

In Fig. 3 the plaster retaining and attach-
ing portions 4 and 5 are the same as that illus-
trated in Fig. 2, but are permanently secured
to the screw 3 by a solder or other extrane- 65
ous fastening material 7.

In Fig. 4 the plaster-retaining portion 8 is
formed integrally with the head 9 of the fas-
tening-screw and provided with a slot 10.

In Fig. 5 the body portion 11 has an aper- 70
ture 12, in which lies the fastening-screw 13,
the body and head being swaged together
and held by frictional contact.

In Fig. 1 I have shown at the right-hand
lower corner a slightly-different form of plas- 75
ter-holder 14 with a retaining portion 15 to
project above the cover, a screw 16 being
provided to pass through the shank 14 into
the side of the box 1.

In Fig. 6 the plaster-holder 17 has a cen- 80
tral aperture 18, threaded to receive the
shank of a screw 19, secured by a lock-nut 20
to a lug 21 in the side of the box 1. The
member 17 in this instance serves to hold the
cover 2 in place. 85

Having thus illustrated and described my
invention fully and various styles of its em-
bodiment, it will be understood that I do not
limit myself to the specific forms shown and
described nor in general otherwise than as 90
set forth in the claims read in connection
with this specification.

What I claim, and desire to secure by Let-
ters Patent, is—

1. A plaster-retaining device for electrical 95
outlet-boxes and the like, comprising a plas-
ter-engaging portion, and an attaching por-
tion having fastening means, substantially as
described.

2. A plaster-retaining device for electrical 100
outlet-boxes and the like, comprising a body
or attaching portion, and a plurality of plas-
ter-engaging wings, substantially as de-
scribed.

3. A plaster-retaining device for electrical 105
outlet-boxes and the like, comprising a body

member having a threaded attaching portion to permit said device to be secured removably to said box, and a plaster-engaging wing, substantially as described.

5 4. A plaster-retaining device for electrical outlet-boxes and the like, said device having means to permit its attachment to said box in position to secure in place the cover of said box, and plaster-engaging means to project

above said cover, substantially in the manner and for the purpose set forth.

Signed at New York city, in the county of New York and State of New York, this 24th day of May, A. D. 1906.

ADNAH McMURTRIE.
